UNITED STATES PATENT OFFICE.

SIMON A. JAROSLAWSKI, OF PARIS, FRANCE, ASSIGNOR TO YBRY, INC., OF NEW YORK,
N. Y., A CORPORATION OF NEW YORK.

DESIGN FOR A BOTTLE OR SIMILAR CONTAINER FOR PERFUMES AND THE LIKE.

Application filed October 15, 1925. Serial No. 15,136. Term of patent 7 years.

To all whom it may concern:

Be it known that I, SIMON A. JAROSLAWSKI, a citizen of the Republic of Poland, residing in the city of Paris, France, have invented a certain new, original, and ornamental Design for Bottles or Similar Containers for Perfumes and the like, of which the following is a specification, reference being had to the accompanying drawing, forming a part hereof.

The figure is a perspective of a bottle or similar container embodying my new design.

I claim:

The ornamental design for a bottle or similar container for perfumes and the like, as shown.

SIMON A. JAROSLAWSKI.
